UNITED STATES PATENT OFFICE.

HARRY E. BARNES, OF TOPEKA, KANSAS.

DESIGN FOR A MUSICAL INSTRUMENT.

45,321.

Specification for Design.

Patented Mar. 3, 1914.

Application filed November 19, 1913. Serial No. 801,993. Term of patent 7 years.

To all whom it may concern:

Be it known that I, HARRY E. BARNES, a citizen of the United States, residing at Topeka, in the county of Shawnee and State of Kansas, have invented a new, original, and ornamental Design for a Musical Instrument, of which the following is a specification, reference being had to the accompanying drawing, forming part thereof.

The figure is a perspective view of a musical instrument, showing my new design.

I claim:

The ornamental design for a musical instrument, as shown.

HARRY E. BARNES.

Witnesses:

CARL P. BOLMAR,
J. M. STARK.
